US0D1083798S

(12) **United States Design Patent** (10) **Patent No.:** **US D1,083,798 S**
(45) **Date of Patent:** **** Jul. 15, 2025**

(54) **USB CHARGER STAND**

(71) Applicant: **Xiangyou Shen**, Ziyang (CN)

(72) Inventor: **Xiangyou Shen**, Ziyang (CN)

(**) Term: **15 Years**

(21) Appl. No.: **29/996,953**

(22) Filed: **Apr. 3, 2025**

(30) **Foreign Application Priority Data**

Mar. 25, 2025 (EM) 015096624-0001

(51) **LOC (15) Cl.** **13-02**

(57) **CLAIM**

The ornamental design for an USB charger stand, as shown and described.

DESCRIPTION

FIG. 1 is a front, right and top perspective view of an USB charger stand, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the USB charger stand that form no part of the claimed design.

1 Claim, 8 Drawing Sheets
